CLAIM

The ornamental design for an end cap for dual filter element, as shown and described.

DESCRIPTION

FIG. 1 is a perspective view of the perspective view of the end cap for dual filter element shown incorporated in its environmental structure:

FIG. 2 is a perspective view thereof, showing a top and a side thereof;

FIG. 3 is another perspective view thereof, showing the top and a side opposite that shown in FIG. 2;

FIG. 4 is another perspective view thereof, showing a bottom and the side shown in FIG. 2;

FIG. 5 is another perspective view thereof, showing the bottom and a side opposite that shown in FIG. 4;

FIG. 6 is a side view thereof, with the opposite side, the front, and the back being identical to that shown in FIG. 6;

FIG. 7 is a top view thereof, with the bottom view being identical to that shown in FIG. 7; and,

FIG. 8 is a cross sectional view taken along line 8-8 in FIG. 2.

The broken lines shown in the views are for illustrating environmental structure, and form no part of the claimed design.
